IMPLANTABLE MEDICAL-ELECTRONIC CIRCUITRY

William M. Chardack, Buffalo, N.Y., assignor to
Medtronic, Inc., Minneapolis, Minn.

Filed Oct. 7, 1969, Ser. No. 19,448

Term of patent 14 years

Int. Cl. D24—02

U.S. Cl. D83—1

Fig 1

Fig 2

Fig 3

Fig 4

Fig 5

Fig 6

FIG. 1 is a front elevational view of implantable medical-electronic circuitry, showing my new design;

FIG. 2 is a right side elevational view thereof;

FIG. 3 is a left side elevational view thereof;

FIG. 4 is a bottom plan view thereof;

FIG. 5 is a top plan elevational view thereof; and

FIG. 6 is a rear elevational view thereof.

I claim:

The ornamental design for implantable medical-electronic circuitry, as shown.
